Primary Examiner — Mark A Goodwin(74) *Attorney, Agent, or Firm* — Dinsmore & Shohl LLP(57) **CLAIM**

The ornamental design for a tray, as shown and described.

DESCRIPTION

FIG. 1 is a lower perspective view of a tray showing our new design;

FIG. 2 is an upper perspective view thereof;

FIG. 3 is a lower view thereof;

FIG. 4 is an upper lower view thereof;

FIG. 5 is a first side view thereof;

FIG. 6 is a second side view thereof;

FIG. 7 is a rear view thereof; and,

FIG. 8 is a front view thereof.

The broken line representations in the figures show unclaimed features, and thus form no part of the claimed design.
